UNITED STATES PATENT OFFICE.

FRANK S. BROADHURST AND LOUIS L. PRATT, OF PHILADELPHIA, PENNSYLVANIA,
ASSIGNORS TO C. H. WHEELER MANUFACTURING COMPANY, OF PHILADELPHIA,
PENNSYLVANIA, A CORPORATION OF PENNSYLVANIA.

ATMOSPHERIC RELIEF-VALVE.

1,099,689.

Specification of Letters Patent.

Patented June 9, 1914.

Application filed October 9, 1912. Serial No. 724,701.

To all whom it may concern:

Be it known that we, FRANK S. BROADHURST and LOUIS L. PRATT, subject of the King of Great Britain and citizen of the 5 United States, respectively, residing in Philadelphia, county of Philadelphia, and State of Pennsylvania, have invented new and useful Improvements in Atmospheric Relief-Valves, of which the following is a 10 specification.

It is the object of our invention to provide a valve which is at once noiseless, sensitive, and certain in operation for controlling low pressure fluid, as for example, low pressure 15 steam, such as existing in the exhaust connection from a turbine, engine, or the like to a condenser, to allow escape or exhaust of such low pressure steam to atmosphere or space at different pressure in case of im- 20 proper working of condenser, or any condition resulting in a rise in pressure or back pressure in such exhaust connection, or any other relation.

It is the further object of our invention 25 to provide a valve of the character referred to which shall operate without dash pots which have been, we believe, on all of the commercially used types of relief valves, whether of single disk type or the multiple 30 disk type which are nevertheless noisy in operation and which rapidly wear.

A further object of our invention is to 35 provide a construction of a valve of the character described in which the individual valves are associated with a deck intervening 40 between atmosphere or space at different pressure and condenser or vacuum connections which are offset with respect to each other, allowing great latitude with regard to the location of the individual valves, and securing other beneficial results.

A further object of our invention is to 45 provide a construction of the individual valves whereby a sensitive easily flexible valve shall be provided to respond to small differences of pressure on opposite sides of the valve and whereby, notwithstanding such flexibility and sensitiveness the valve proper shall fit its seat so snugly that there 50 is economy in consumption of sealing water and in addition the prevention of flow of excess sealing water through the valve into the space from which the steam or other low pressure fluid is to escape through the valve.

Our invention resides in the features of 55 construction and application hereinafter described and claimed.

For an illustration of some of the forms our invention may take reference is to be had to the accompanying drawings, in 60 which:

Figure 1 is a perspective view of one form of our invention. Fig. 2 is a top plan view of the valve deck and valves and associated vacuum or condenser connection. 65 Fig. 3 is a longitudinal cross section through a valve as illustrated in Fig. 1. Fig. 4 is a perspective view of one of the valve spin- 70 dles or shafts. Fig. 5 is a perspective view of a valve spindle crank. Fig. 6 is a per- 75 spective view of a portion of the mechanism for operating all the valves.

Referring to Fig. 1, the connection to condenser, vacuum, or exhaust connection between turbine, engine or the like, and 75 condenser is shown at 1, in this case, for example, a cylindrical pipe having the flange 2 for bolting to a similar flange or the like of a pipe communicating with the vacuum condenser, or exhaust connection. The atmospheric connection, or connection to space at different pressure or means for communicating with the outer atmosphere is shown at 3 as a similar pipe having flange 4 for bolting to a similar flange of a pipe ex- 80 tends to atmosphere or space at different pressure. The pipe connection members or branches 1 and 3 are not in alinement, but are preferably though not necessarily off- 85 set with respect to each other and with re- 90 spect to the valve deck 5 located between them and secured by bolts 6 to the flange 7 preferably cast integral with the member 1. And preferably cast integral with the mem- 95 ber 3 is the member 8 having the flange 9 secured by bolts 10 to the flange 7 of the member 1. The chamber 8 has the remov- 100 able cover 11 secured by bolts 12, the re- 105 moval of the cover 11 uncovering an open- 105 ing allowing access to the valves.

It will be noted that the valve deck 5, secured to the member 1, is preferably in- 110 closed within the chamber 8, as indicated in Fig. 3. In the example illustrated the valve deck 5 is provided with six valve 105 seats 14 inclined with respect to the deck and each covered by a rigid separate valve plate 15 faced and ground to seat 14 and

held by bolts 16 to the phosphor bronze or other suitable spring 17 coiled at 18 about the valve spindle 19, wholly within the casting, having the longitudinal slit 20 in which 5 the inner end of the spring 17 engages and is secured. In the example shown there are three valve spindles 19, each co-operating with two valves. The spindles 19 have bearings in lugs 21 preferably carried by 10 the deck 5. Secured upon each spindle 19 is a crank 22 and to the outer ends of these cranks is pivoted a bar 23, to cause these cranks and their attached spindles to move in unison with each other. One of these 15 cranks, as 22, Fig. 5, is provided with a socket 24 adapted to receive the lug 25 on the shaft 26, Fig. 6, which latter extends from within the casing 8 to the exterior thereof and on its outer end is secured the 20 hand lever 27 having the hand clamp 28 extending through a slot 29 in the arc shaped member 3, the clamp 28 serving to clamp the handle 27 in any desired position to which it may be moved, its movement 25 communicating movement through shaft 26 to the associated crank 22 and through it to its spindle 19 and through the bar 22 and the other cranks to the remaining spindles 19. Angular movement of the handle 27 rotates all the spindles 19 to either adjust the 30 tensions of the springs 17, or to lift all the valves entirely clear from their seats 14. Normally the springs 17 are adjusted to press the separate valve plates 15 against 35 their seats 14, so that the valves are biased to a degree against opening.

Communicating with the interior of the chamber 8 is a pipe 31 provided with a valve 32 admitting water or the like into the chamber 8 to provide a water seal for all the 40 valves. The water rises to the level of the outlet pipe 33, Fig. 1, and overflows into the funnel 34 to which a waste pipe may be connected at 35. The valve 32 is opened only 45 far enough to allow a flow of water into the chamber 8 sufficient to cause only a slight overflow through pipe 33, the overflow being visible as it drops from pipe 33 into funnel 34. Between the member 1 and the 50 chamber 8 is a wall or web or dam 36 disposed at a level somewhat higher than the level of the outlet pipe 33. The height of the pipe 33 is so determined that there will be within the chamber 8 a body of water 55 submerging all the valves at least to a point slightly higher than the highest point of any of the seats 14. This produces, as stated, a water seal for all the valves insuring their remaining tight in service where the atmosphere or space at different pressure exerts a pressure upon the tops of the valves. By the arrangement shown the sealing water, rises to the same height with respect to all the valves, giving an equal head over 60 all the valves. And we believe we are the

first to apply a water seal to valves of the type here disclosed, that is, in a relation where the valves are required to operate in conjunction with low pressure steam to allow the escape thereof to outer atmosphere or space at different pressure, a vacuum or lower pressure normally existing on the under side of the valves.

In case of improper operation of the condenser or in case of any other condition arising which will reduce the vacuum and increase the pressure on the exhaust side of a turbine, engine, or the like, such increased pressure, though *per se* a low pressure, will actuate the valves in opposition to their springs and allow escape of the steam or other low pressure fluid directly to atmosphere or other space through the valves, chamber 8 and connection 3.

We are aware that in atmospheric relief valves a plurality of valve units have been provided, of a disk type or multiple disk type. We believe that in such cases the valves have been controlled whenever used in practice by dash pots and that even then they have been noisy in operation and subject to rapid wear of the valve seats. By the employment of the type of valve herein described, however, the operation is certain, sensitive, and noiseless, without recourse to dash pots or the like.

It is to be understood that the valve deck 5 need not be horizontal, as illustrated in Figs. 1, 2 and 3, but that the same may be inclined or even vertical.

It will be noted that the valve deck 5 has been made substantially square; it may be square but in any event is preferably rectangular so that all the valve spindles 19 will be of the same length, which they would not otherwise be if the individual valves were distributed in such fashion as to conform to a circular or other shape of deck in which case the valve spindles 19 would be of different lengths and therefore introduce greater expense in cost of manufacture and difficulty and confusion in supplying spare or repair parts.

While we have referred to our valve as intervening between a vacuum and atmosphere it is to be understood that it may be employed in other relations where it is to respond to relatively small differences in pressure on opposite sides of the valve.

What we claim is:

1. A valve mechanism responsive to small pressure differences comprising an inclosed substantially horizontal valve deck, fluid connections on opposite sides of said deck, a plurality of individual independently operable valves on said deck, a web common to all said valves intervening between said deck and the opening of one of said fluid connections, and means for supplying sealing liquid to said valves over said deck, said

web preventing flow of sealing fluid into said fluid connection.

2. A relief valve structure comprising fluid connections offset with respect to each other, a casing member integral with one of said connections, a dividing wall common to said connection and said casing, said wall having an aperture forming communication between said connection and said casing, a valve deck intervening between said casing and the other of said connections, and valve adjusting means extending through a side wall of said casing.

3. A relief valve structure comprising fluid connections offset with respect to each other, a casing member integral with one of said connections, a dividing wall common to said connection and said casing, said wall having an aperture forming communication between said connection and said casing, a valve deck intervening between said casing and the other of said connections, and valve adjusting means extending through a side wall of said casing.

25 4. The combination with fluid conducting connections, of a valve deck intervening between said connections, a plurality of valve seats on said deck, a rigid valve plate adapted to snugly fit each valve seat, valve spindles, and a spring separate and distinct from said valve plate attached to said valve plate and coiled about and attached to one of said spindles, said valve deck being substantially rectangular and said spindles all of substantially the same length.

30 5. The combination with fluid conducting connections, of a valve chamber intervening

ing between said connections, a valve deck housed completely within said chamber, a plurality of valve seats on said deck, a valve 40 coöperating with each valve seat, said fluid conducting connections being offset with respect to each other, said chamber having a removable wall inclined with respect to said valve deck.

45 6. The combination with fluid conducting connections, of a valve chamber intervening between said connections, a valve deck housed completely within said chamber, a plurality of valve seats on said deck, a valve 50 coöperating with each valve seat, spindles for said valves disposed substantially parallel with said valve deck, means housed within said chamber connecting said spindles together, and means extending to the exterior 55 for operating said spindles in unison.

7. The combination with fluid conducting connections, of a valve chamber intervening between said connections, a valve deck housed completely within said chamber, a 60 plurality of valve seats on said deck, a valve coöperating with each valve seat, means for water sealing said valves, and a web intervening between one of said connections and said chamber preventing entry of said sealing water into said connection.

In testimony whereof we have hereunto affixed our signatures in the presence of the two subscribing witnesses.

FRANK S. BROADHURST.

LOUIS L. PRATT.
